UNITED STATES PATENT OFFICE.

HOMER A. SAMPSELL, OF SALEM, OHIO.

CAR-COUPING.

SPECIFICATION forming part of Letters Patent No. 258,320, dated May 23, 1882.

Application filed February 9, 1882. (No model.)

To all whom it may concern:

Be it known that I, HOMER A. SAMPSELL, a citizen of the United States of America, residing at Salem, in the county of Columbiana and State of Ohio, have invented certain new and useful Improvements in Automatic Railroad-Car Couplings; and I do hereby declare the following to be a full, clear, and exact description of the invention, such as will enable others skilled in the art to which it appertains to make and use the same, reference being had to the accompanying drawings; and to the letters or figures of reference marked thereon, which form a part of this specification, and in which—

Figure 1 is a longitudinal vertical section showing the tumbling-latch holding the pin up ready to receive the link. Fig. 2 is a longitudinal vertical section showing the tumbling-latch pushed back by the entering link and the pin down. Fig. 3 is a cross-section taken on the line of the pin. Fig. 4 is an isometrical projection of the tumbling-latch.

A represents a draw-head for railroad-cars, provided with a cavity, B, of suitable size and form, for the reception of a tumbling-latch, C, of peculiar construction. The cavity extends forward to the pin-hole D and communicates with the back end of the mouth E of the draw-head, so as to admit the link M. The lower side of the cavity is open, so as to permit of the insertion and withdrawal of the tumbling-latch. The tumbling-latch C is hung upon a pin, G, which passes through the sides of the draw-head and through an oblong slot, H,

set at an angle of about forty-five degrees and near the end of the latch. The front end of the latch terminates in a toe or projection, I, and face J, the toe being hollowed out in a circular form, with a ledge, K, for holding the pin suspended in making the automatic coupling.

In operating this device the pin L is raised in the draw-head, allowing the tumbling-latch to fall to the position shown in Figs. 1 and 3 of the drawings, the pin G being at the upper end of the slot H. The pin is then lowered and allowed to rest upon the ledge K, ready for the reception of the link M, which may now be inserted in the mouth of the draw, and, striking the face J, force the tumbling-latch backward and upward the full length of the slot H, thereby drawing the ledge K from under the pin L and allowing it to drop down through the link.

Having thus described my invention, I claim as new and desire to secure by Letters Patent—

An automatic car-coupling consisting of the draw-head A, having within it the latch-block constructed with a flat projecting lip for the support of the coupling-pin, and an angular slot to move upward and backward in parallel lines by the pressure of the connecting-link, substantially as described.

In testimony whereof I affix my signature in presence of two witnesses.

HOMER A. SAMPSELL.

Witnesses:

GEO. HOLMES,
IRA E. SAMPSELL.
